UNITED STATES PATENT OFFICE

HARRY MINTZ, OF DORCHESTER, MASSACHUSETTS

COUCH HAMMOCK

Application filed June 5, 1929. Serial No. 368,534.

This invention relates to couch hammocks of the type in which a seat frame, provided with an adjustable back rest, is suspended for transverse swinging movement between stationary end supports; and the principal object of the invention is to provide improved means for removably mounting the back rest upon the seat frame, whereby the back rest may be moved angularly with respect to the seat and may be supported at an adjusted inclination thereto.

A recommended embodiment of the invention is illustrated in the accompanying drawings, in which:

15 Fig. 1 is an end elevation of a couch hammock equipped with the improvement;

Fig. 2 is an enlarged sectional detail taken on line 2—2 of Fig. 1; and

20 Fig. 3 is an enlarged detail of one of the back rest mountings.

It will be understood that the couch and its upright end supports may be fashioned in any appropriate manner of any suitable materials in accordance with customary practice for the particular purpose to be served. The general structure illustrated in Fig. 1 is accordingly representative of a typical construction at the opposite ends of the article, the ends being substantially identical. As

25 shown, the couch hammock comprises spaced end frames or standards each including a base member 3 and a horizontal rail 4 rigidly connected by upright posts 5; a seat frame 6 being shown as having a cushion 7, and provided with a back frame 8 suitably mounted thereon for relative angular movement, the back rest or frame being illustrated as having a cushion 9 or other upholstery; and suspension means, such as the straps or links 10

30 separably connecting the outer ends of the rail 4 with braced legs 11 of the seat frame 6, for supporting the couch between the end standards. Thus the couch unit, including the seat and back rest, is suspended between

35 the removable uprights for swinging movement in a front and rear direction.

The combined arm rest and adjustable support for the back rest preferably comprises a metal tube or rod 12, bent as at 13 and having flattened ends 14 and 15. The forward end

14 is pivoted as by pin 16 to the front corner of the seat frame 6, and the rear end 15 has a longitudinal slot 17 receiving a stud 18 fixed in the back frame 8. The material along the upper side of the guide slot or recess 17 is 55 provided with spaced recesses or notches 19, or other rack-like formations, selectively engageable over the stud 18 to lock the bar or tube 12 in adjusted position. Hence, the inclination of the back rest may be varied by lifting the bar end 15 and sliding the stud along the guide slot by tilting the back to the desired position, and then dropping or depressing the bar to engage the stud in one of the notches 19.

The back frame is preferably mounted for angular movement with respect to the seat frame by the separable connection illustrated in Fig. 3 in which the end member of the back frame is shown at 8 and longitudinal angle iron at the rear of the seat frame is shown in section at 20. The lower end of the frame member 8 has a wide-mouthed slot 21 opening at its inner corner and extending diagonally of the member in an upward direction. The vertical web 22 of the seat frame member 20 is loosely received within said slot whereby the back frame 8 may be swung forwardly and rearwardly on said web 22 to an extent dependent upon the width 75 of the slot 21. The back frame may thus be dropped into place upon the seat frame when the former is substantially vertical, so that the upper end of the slot 21 seats upon the edge of web 22; and a locking tongue 23 80 is preferably provided at the lower outer corner of frame member 8 to project under the angle iron 20 and thereby prevent detachment of the back frame when it is tilted rearwardly. (Fig. 3.) The removable back rest may be supported as thus described by the two transverse frame members 8 at its opposite end, without special fastenings or hinge members; and may be held at the desired inclination by the locking bar 12. 85

The rigid locking bar not only supports the back rest in adjusted position against angular movement in either direction, but also serves as a convenient arm rest at the end of the couch. The arm rest is carried 100

by the suspended couch, independent of the end standards, and consequently affords a more comfortable support for the arm, particularly when the couch is swinging back and forth; and the effective length of the link connection between the arm rest and the back rest may easily be adjusted by hand without the use of special tools or the removal of the attaching elements.

10 I claim:

1. A couch hammock of the class described, comprising a seat frame having an upstanding web at the back thereof, a back frame having a supporting member provided with a diagonal slot opening at its forward corner and receiving said web, whereby the back frame is removably mounted on said web for angular movement with respect to the seat frame, and means for holding the back frame in adjusted position with relation to the seat frame.

2. A couch hammock of the class described, comprising a seat frame having an upstanding web at the back thereof, a back frame having a supporting member provided with a diagonal slot opening at its forward corner and receiving said web, whereby the back frame is removably mounted on said web for angular movement with respect to the seat frame, the lower end of the supporting member constituting a locking tongue normally hooking under said web so that the back frame can not be removed until said member is tilted forwardly of the plane of said web, and means for holding the back frame in adjusted position with relation to the seat frame.

Signed by me at Boston, Massachusetts,
this 9th day of May, 1929.
